IRONING BOARD

Manuel Fernández, Covington, La.

Application May 7, 1940, Serial No. 333,839

4 Claims. (Cl. 38—123)

This invention relates to an ironing board and it consists in the constructions, arrangements and combinations herein described and claimed.

It is the cardinal object of the invention to 5 provide an ironing board which may be quickly erected for use or folded to a collapsed position for the purpose of storage or otherwise.

It is a particular object of the invention to provide a novel locking means for the support legs 10 and braces of the ironing board, which is gravity actuated to releasing position and automatically moved to locking position when the board is erected for use.

It is also an important object of the invention 15 to provide an ironing board of the kind stated in which a minimum of parts are required, and which are of simple construction, enabling the construction of an ironing board at a low cost.

20 Additional objects, advantages and features of invention will be apparent from the following description considered in conjunction with the accompanying drawing, wherein

Figure 1 is a side elevation of the board in 25 erect position.

Figure 2 is an enlarged rear elevation thereof.

Figure 3 is an enlarged vertical sectional view on the line 3—3 of Figure 2.

Figure 4 is a side elevation of the board in 30 partly collapsed position.

Figure 5 is a fragmentary top plan view of certain of the locking elements embodied in the board.

Figure 6 is a perspective view of certain of the 35 locking elements in detached relation.

There is illustrated generally, an ironing board 10 which embodies a work board 11, the latter being of any conventional design and of any desired length and width.

40 The board 11 is preferably braced longitudinally, as at 12, the braces being positioned inwardly of the longitudinal sides of the board as clearly shown in Figure 2, and are located medially of the point of support of upright legs 13.

45 Rearwardly of the braces 12, two pairs of ears 14 are fixed to the under side of the board, between each pair of which a forwardly extended diagonal leg 15 is pivotally mounted, the legs 15 being approximately the same length as the board 11. A leg 13 is pivotally connected to respective legs 15, as at 16.

Forwardly of the braces 12 and in the medial longitudinal center of the board 11 a pair of ears 17 are provided, between which there is pivotally 50 mounted a brace rod 18, the construction and

function of which will be described hereinafter.

The legs 13 are braced and spaced apart by a pair of rungs 19 and 20, each of which has a vertically extending bore 21 positioned medially of the length of the rungs 19 and 20, and which receive slidably therethrough a locking rod 22.

A portion of the rod 22 next adjacent the rung 19 is of reduced diameter, providing a shoulder 23 which cooperates with a stop plate 24, fixed to the upper face of the rung 19, thus limiting 10 downward sliding movement of the rod 22.

The rod 22 is of a length slightly greater than the spacing of the rungs 19 and 20, so that in normal erect position of the ironing board the rod will project upwardly through the upper rung 15 20, for a purpose as will presently appear.

Upon the inner face of the rung 20, there is mounted a guide and retainer plate 25, having an L-shaped formation, the angle portion 26 extending forwardly at right angles to the rung 20 20. The plate 25 has a slot 27 formed therein, extended vertically thereof and forwardly of the portion 26 as clearly shown in Figure 6. The plate 25 is so positioned and fixed to the rung as to align the slot 27 with the bore 21 of the rung. 25

A brace rod 28 is pivotally mounted between the legs 15 by means of a transverse pintle 29, the forward end of the rod 28 having a lock plate 30 secured to the underside of the brace and slidably extended through the slot 27 of the guide plate 25. As may be seen in Figure 5, the plate 30 has a broadened head 31 of a width greater than the slot 27 so as to limit the backward movement of the plate and to align an opening 32 with the bore 21. The plate 30 also has a right 35 angularly disposed portion 33 extended vertically, apertured as at 34, adapted to slidably receive a tongue 35 of the brace 18. The tongue 35 has its extremity 36 disposed at a slight angle so as to snugly rest upon the lock plate 30, and has an oval-shaped aperture 37 through which the rod 22 may be extended. Preferably, the tongue 35 is of a length to project slightly beyond the portion 33 when in erect or operative position of the board. 45

If desired, or found necessary, the legs 13 may be additionally braced adjacent their upper ends by a rung 38. The rung 38 will have an offset medial portion 39 for accommodation of the brace 18 when in folded position.

50 The plate 30 is illustrated as screw-fastened to the bar 28 and in order to accommodate the heads of the screws during sliding movements of the bar 28 through the slots 27 and 34, the rung 20 is provided with a channel 40.

- The operation of collapsing the board will be substantially as follows: The ironing board is raised so that the legs 13 are lifted from the floor, allowing the rod 22 to slide downwardly through the openings 24 until checked by the plate 24 which engages the shoulder 23 of the rod. Obviously, the plate 30 and the tongue 35 are released, the bar 28 and associated plate 30 moving through the slot 27 while the tongue 35 and complementary brace 18 pass through the slot 34 as clearly shown in Figure 4. The folding action is then continued until the several parts are brought to rest against the underside of the board 11.
- To set up the board to an operative position, it is only necessary to swing the legs 13 to right angles with the board 11, which will move the legs 15 to their normal position by virtue of the brace 28 and the brace 18 will be drawn to its operative position by movement of the board 11. The head 31 will limit or stop movement of the braces by reason of contacting engagement with the plate 25, and in this position of the parts the rod 22 will pass upwardly through the aligned openings 32 and 36 when the legs 13 are rested upon the floor.

While I have shown and described a preferred construction, this is by way of illustration only, and I consider as my own all such modifications in structure as fairly fall within the scope of the appended claims.

I claim:

1. In an ironing board, a pair of legs pivotally connected to one end thereof, a leg pivotally connected to each of the first named legs and having its upper end in bearing engagement with the underside of the board, said second named legs having a pair of vertically spaced rungs, a rod slidably mounted through the rungs, a brace pivotally connected to the first named legs and having an aperture aligned with and engaged by the rod in erected position, a brace pivotally connected with the board and having an apertured portion adapted to align with and receive the rod therethrough in erected position, guide means for aligning said apertures with the rod, said rod being of a length to be projected through the apertures of the braces when the second named legs are engaged upon a floor and means for slidably connecting the braces adjacent their free ends.

2. The structure of claim 1 in which one of the rungs includes stop means for limiting downward sliding movement of the rod.

- 55 3. In an ironing board, a pair of normally dis-

posed diagonal legs pivoted to one end thereof, a normally vertical leg pivoted to each of the diagonal legs, the upper end of the vertical legs being in contacting engagement with the underside of the board, said vertical legs having a pair of vertically spaced rungs, each of the rungs having a vertically disposed bore, a rod slidably mounted through the bores of the rungs, a brace pivotally connected to the diagonal legs intermediate their lengths, said brace having an apertured portion adapted to align with and receive the rod therethrough in erected position, a brace pivotally connected with the board and having an apertured portion adapted to align with and receive the rod therethrough in erected position, 15 guide means for aligning said apertures with the rod, said rod being of a length to project through the aligned apertures of the braces when the vertical legs are engaged upon a supporting surface, means for slidably interconnecting the braces 20 adjacent their free ends, and means for limiting the downward sliding movement of the rod.

4. In an ironing board, a pair of normally disposed diagonal legs pivoted to one end thereof, a normally vertical leg pivoted to each of the diagonal legs, the upper end of the vertical legs being in contacting engagement with the underside of the board, said vertical legs having a pair of vertically spaced rungs, each of the rungs having a vertically disposed aligned bore, a rod slidably mounted through the bores of the rungs, a guide plate fixed to the upper rung, the guide plate having an opening therethrough, a brace pivotally connected to the diagonal legs intermediate their lengths, said brace having a plate 35 fixed to its free end and extended through the opening of the guide plate, said plate having an abutment means near the free end consisting of a head of greater width than the opening to limit outward movement of the brace, and terminating in an upwardly extended apertured plate, a brace pivotally connected with the board and having a tongue adapted to flatly abut upon the head of the plate and of a width to pass through the opening of the upwardly extended plate, said head 40 and tongue having apertures aligned with the bores of the rungs in erected position, said rod being of a length to be projected through the aligned apertures of the braces when the vertical legs are engaged upon a supporting surface, 50 said rod having a reduced diameter adjacent its lower end, and a stop plate on the lower rung positioned within the reduced portion whereby to limit the downward movement of the rod.

MANUEL FERNÁNDEZ. 55
